UNITED STATES PATENT OFFICE.

PHILIP BOURNE, OF BROOKLYN, NEW YORK.

ASH-CART.

SPECIFICATION forming part of Letters Patent No. 415,895, dated November 26, 1889.

Application filed March 27, 1889. Serial No. 304,936. (No model.)

To all whom it may concern:

Be it known that I, PHILIP BOURNE, of Brooklyn, in the county of Kings and State of New York, have invented a new and Improved Ash-Cart, of which the following is a full, clear, and exact description.

The ordinary form of ash-cart is exceedingly objectionable, inasmuch as no proper provision is made in their construction to prevent the blowing away of dust. It is to overcome this objection and provide a cart that is necessarily closed when the driver stands upon the foot-board that I have designed the ash-cart forming the subject-matter of this application, the invention consisting, essentially, of a cart-body provided with hinged covers or lids and a sectional movable foot-board, such connections being arranged between the foot-board and the covers, that when the foot-board sections are pressed down the covers will be closed.

The invention further consists of certain novel constructions, arrangements, and combinations of elements whereby the general efficiency of the cart is materially increased, all as will be hereinafter fully explained, and specifically pointed out in the claims.

Reference is to be had to the accompanying drawings, forming a part of this specification, in which similar figures of reference indicate corresponding parts in all the views.

Figure 1 is a side view of my improved ash-cart. Fig. 2 is a side view of my improved ash-cart, the right-hand wheel being removed and one of the lids being shown in a raised position. Fig. 3 is a front view of the cart, the front panel being removed. Fig. 4 is a cross-sectional view looking toward the front of the cart, the view being taken on line $x x$ of Fig. 2. Fig. 5 is a sectional plan view on line $y y$ of Fig. 3; and Fig. 6 is a front face view of the cart, the front panel being removed, the view representing a modified construction.

In the drawings, 10 represents the cart-axle, said axle being cranked and provided with inwardly-extending trunnions 11, upon which the cart-body bearings 12 rest. The crank-axle 10 is formed with forwardly-extending arms 13, to which the butt-ends of the shafts 15 are secured; or the parts might be ar-

ranged as represented in the drawings, wherein I have shown a frame 16 as being secured to the arms 13 and the shafts 15 as being bolted to this frame.

The cross-piece 17 of the shafts 15 carries a turn-button 18, that is arranged to engage the forwardly-extending tongue 19, carried by the cart-body 100, this tongue being slotted to receive the turn-button. To the tongue 19 or arm 19, I hinge foot-boards 20, said foot-boards being provided with stirrups 21, such stirrups extending downward from the sides of the shafts when the foot-boards are in a horizontal position.

In order that the cart may be effectually closed, I provide it with covers or lids 23, said covers or lids being hinged to a ridge-pole 24. Each of the covers carries a forwardly-extending stud or pin 25, which rides in a curved slot 26, formed in the front of the cart-body, the studs carrying slotted links 27, which said links are connected to a plate 30, that is mounted to slide in ways 31, the connection between the links and the plate being established by means of studs 28, that pass through the link-slots. To the lower end of the plate 30, I secure a cross-bar 31^a, provided with two forwardly-extending projections 32, above which the foot-board sections 20 extend. The plates and the links connected thereto are housed within the front wall of the cart-body, and in order that all dust may be prevented from entering this housing I connect semi-circular disks 3 to each of the lids or covers.

From the construction above described it will be seen that when either of the lids or covers is raised to the position in which one of the lids is shown in Figs. 2 and 3 the plate 30 and the cross-bar carried thereby will be raised, and as the plate is so raised the foot-board sections will be moved to the position in which they are best shown in Fig. 3, and will be there retained until the lid is closed, thus making it impossible for the driver to mount the cart and drive away without closing the lid.

In filling the cart the raised lid acts as a shield or guard, and to a great extent prevents the flying of dust and ashes.

By cranking the axle and mounting the cart-body as above set forth I obviate the

necessity of throwing the ashes to such a height as would be necessary if an ordinary straight axle were employed.

In mounting the lids or covers provision 5 should be made for their easy removal in case of necessity.

In certain cases it might be desirable that only one cover should be raised at a time, and to this end I would employ such an attachment as is represented in Fig. 6, wherein I have represented the studs or pins 25 as extending forward to pass through slots *n*, that are formed in a rod or bar 60, the arrangement being such that when one of the covers— 15 for instance, the cover upon the left—is raised to the position in which it is shown in dotted lines in Fig. 6 the rod or bar 60 will move to the position in which it is shown in dotted lines, and when in this position any upward 20 movement of the lid or cover upon the right would carry the lower end of the rod or bar against a stop 61.

To relieve the parts housed in the forward portion of the cart from any undue strain, I 25 prefer to provide the lids with stop-blocks 62, but this is not essential.

Having thus described my invention, I claim as new and desire to secure by Letters Patent—

1. The combination, with a cart-body, of a 30 lid hinged thereto, a movable foot-board, and connections between the foot-board and the lid, as and for purpose stated.

2. The combination, with a cart-body, of a lid hinged thereto, a slide, connections between 35 the slide and the lid, a movable foot-board, and connections between the foot-board and the slide, substantially as described.

3. The combination, with a cart-body, of a lid hinged thereto, a link connected to the lid, 40 a slide to which the link is connected, projec-

tions extending forward from the slide, and a hinged foot-board, said foot-board resting upon the forwardly-extending projections, substantially as described.

4. The combination, with a cart-body, of a 45 lid hinged thereto, a slotted link connected to the lid, a slide, a stud extending through the link-slot to connect with the slide, an arm carried by the slide, a movable foot-board, and a projection carried by the arm, 50 said projection being arranged beneath the foot-board, substantially as described.

5. The combination, with a cart-body, of a 55 forwardly-extending tongue secured thereto, foot-board sections hinged to the tongue, lids hinged to the cart-body, slotted links carried by the lids, a slide, studs carried by the slide and extending through the link-slots, a cross-bar carried by the slide, and projections carried by the cross-bar and arranged to extend 60 beneath the foot-board sections, substantially as described.

6. In a cart, the combination, with a cranked axle, of inwardly-extending trunnions carried thereby, and a cart-body provided with 65 bearings which rest upon said trunnions, substantially as described.

7. The combination, with a cart-body, of 70 lids hinged thereto, slotted links carried by the lids, a slotted bar arranged in connection with the links, a slide, studs carried by the slide and extending through the link-slots, a cross-bar carried by the slide, projections carried by the cross-bar, and foot-board sections against which the projections bear, 75 substantially as described.

PHILIP BOURNE.
